WATERING BOWL AND A MEANS FOR SUPPORTING THE SAME

Filed Nov. 12, 1928

UNITED STATES PATENT OFFICE

ROBERT HAMILTON BROWN, OF OTTAWA, ONTARIO, CANADA

WATERING BOWL AND A MEANS FOR SUPPORTING THE SAME

Application filed November 12, 1928, Serial No. 318,734, and in Canada September 12, 1928.

This invention relates to watering bowls and a means for supporting the same, whereby the bowls will be held in rigid relationship to the bracket connected to the upright on 5 which it is retained.

The principal object of my invention is to provide for the rigid supporting of the bowls in such a manner that the interlocking parts will be fixedly and positively retained in 10 proper position so as to eliminate the constant possibility of having these parts displaced during the feeding of the animals.

A further object of my invention is to provide for the rigid supporting of the bowls 15 from one side adjacent the top and bottom of the same in such relationship to the bracket from which it is supported, that the bowl may be removed or placed in position while being held in a horizontal position.

20 A further object of my invention is to provide a means of rigidly supporting the bowls, comprising a bracket, having integral, spaced lugs, the outer contour of which conforms to the contacting face of the upright on which 25 it is retained.

With the foregoing and other objects in view as will appear as the description proceeds, the invention consists of the novel construction, combination and arrangement of 30 co-operating elements as hereinafter more specifically set forth, claimed and shown in the accompanying drawing forming a part of the present application, in which:

Fig. 1 is a side plan view of the preferred 35 embodiment of my invention.

Fig. 2 is a sectional view taken on line 2—2 of Fig. 1.

Fig. 3 is a detail view of a section of the bowl looking from the outside towards the 40 engagement lugs.

Fig. 4 is shown to illustrate the position of the bowl during the removal or positioning of the same from or to the bracket.

Like numerals of reference designate corresponding parts throughout the different views.

5 is an upright which may be of cylindrical form or provided with multilateral surfaces, the purpose of which will hereinafter be set forth. 6 is a bracket, having a central open-

ing extending longitudinally therethrough and provided with an interior threaded portion adjacent each end. A water pipe 7 may be threadedly connected to either of these portions and a plug 8 would be used to close the other of said portions. Each end of the bracket 6 is provided with an annular flange 6^a to strengthen these end portions in which the pipe 7 may be connected. The bracket 6 is provided with integral spaced lugs 9, which lugs are preferably of angle-iron formation, one portion 9^a of which extends longitudinally parallel on each side of the portion of the bracket adjacent the upright 5 while the other portion 9^b of the angle-iron formation extends outwardly towards the upright 5 and is provided with an outer contour conforming in shape to that portion of the upright with which it is to contact. 10 are U-shaped clips fitting around the upright 5 and having their ends extended through openings formed in the portions 9^a. The nuts 11, threadedly engaged on the ends of the clips 10, retain the lugs 9 in proper contact relationship with the upright 5.

Integral with and extending outwardly adjacent the upper end of the bracket 6, I provide a supporting means 12 for the top of the bowl, the water control valve and the animal control lever for operating the valve. On each side of this supporting means, I provide outwardly extended lugs 14. 15 is the bowl, which is provided with a rearwardly extending portion 16 to accommodate the valve 17 and the means for controlling the same. The rear wall of this portion 16 extends upwardly to provide the bifurcated locking lug 18, which lug straddles under the supporting means 12. The edge of the bowl adjacent the lug 18 is notched at both sides to engage the lower edge of the lugs 14.

19 is an integral rib extending rearwardly of the portion 16. The bracket 6 is provided with co-acting forwardly extended lugs 20, between which the rib 19 will fit snugly. 21 is the pin extending through oppositely registering openings in the lugs 20 and the rib 19. A cotter pin is used to retain the pin in proper position. The spaced lugs 20 act as a guide-way in which the rib may be moved in vertical 100

direction during the removal or positioning of the bowl.

22 is the animal control lever for operating the valve 17. This lever is pivotally supported on the free end of the arm 12^a extending downwardly from the forward end of the supporting means 12.

The construction as disclosed in this application sets forth a means for supporting watering bowls designed to overcome undesirable

10 features which have been found by actual experience in handling bowls now being used by the public. I provide a simple and efficient construction, whereby the interlocking parts provide positive means for retaining

15 the bowl in proper position and eliminate unnecessary parts which are commonly subject to displacement during the feeding of the animal or accidentally by the stableman while working around the stalls. Furthermore,

20 there is a very important feature in my construction in that the bowl may be removed or placed in position while being held in a horizontal position.

With the common constructions now on the market, many of the valve

25 connections and animal lever connections are broken off or bent, during the removal or placing in position of the bowls, which will often cause leaking or stoppage of the water.

In the construction disclosed in this application, the interlocking parts are so designed as to provide for the rigid and positive retaining

30 of the bowl in proper position. But, when found necessary to remove the bowl, the pin

21 may be taken out and the bowl 15 lowered

35 from the position A of Fig. 4 to the position B of Fig. 4, the rib 19 sliding down between

the lugs 20. The bowl is then brought to the

40 position C of Fig. 4. It will be noted that in all three positions A, B and C, during the removal of the bowl, it remains in horizontal

45 position. The common construction now in use require to be hinged or tilted before their interlocking parts may be disengaged, which necessitates that the normal water in the bowl

50 will have to be dumped out or dumped onto the floor.

The foregoing specification and annexed drawing disclose the preferred embodiment of my invention, but it is to be understood that minor changes may be resorted to in the commercial adaptation of my invention without departing from the scope of the invention as hereinafter claimed.

55 What I claim as new is:

1. In means for supporting a bowl, the rear wall of which extends upwardly to provide a bifurcated lug; said bowl having a notch formed in the upper edge thereof adjacent each end of said lug, and an integral rib extending outwardly from said rear wall, a hollow bracket provided with a supporting means adjacent its upper end; an outwardly extended lug on each side of said supporting means adapted to be interlocked by said

bifurcated lug and seated in said notches; co-acting lugs integral with said bracket, the lower portion of said rib snugly fitting between last said lugs, a pin for retaining said rib in proper position, water connections to said bracket and a means for supporting said bracket on an upright the construction being such as to permit placement and removal of the bowl while being held in horizontal position.

2. In means for supporting a bowl, a bracket, a means for interlocking the upper edge of said bowl adjacent the upper end of said bracket when said bowl is raised to interlocking position, a rearwardly extending rib on said bowl, a guideway on said bracket, a means for fixedly retaining said rib in said guideway when in normal position and said guideway permitting said rib to be moved vertically therein when said bowl is being lowered from its interlocking position, while being held in horizontal position.

In testimony whereof, I affix my signature.

ROBERT HAMILTON BROWN.
